G. THOMPSON,
TELEPHONE EXCHANGE SYSTEM,
APPLICATION FILED AUG. 7, 1919.

Patented July 5, 1921.

Inventor:
George Thompson
by
F. Roberts Atty.

UNITED STATES PATENT OFFICE.

GEORGE THOMPSON, OF MOUNT VERNON, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,383,677.

Specification of Letters Patent.

Patented July 5, 1921.

Application filed August 7, 1919. Serial No. 315,820.

To all whom it may concern:

Be it known that I, GEORGE THOMPSON, a citizen of the United States, residing at Mount Vernon, in the county of Westchester, State of New York, have invented certain new and useful Improvements in Telephone-Exchange Systems, of which the following is a full, clear, concise, and exact description.

10 This invention relates to improvements in telephone exchange systems and has particular reference to a circuit arrangement for line switches.

15 An object of the invention is to cause a line switch to test for an idle trunk by means of the stepping magnet of said switch.

20 In accordance with this object, the stepping magnet is preferably provided with a differential winding which permits the magnet to operate the switch over terminals of busy trunks, but which prevents further operation of said magnet when the brushes of the switch engage the terminals of an idle trunk.

25 The inventive idea involved is capable of receiving a variety of expressions, one of which, for the purpose of illustrating the invention, is shown in the accompanying drawing; but it is to be expressly understood that 30 said drawing is employed merely for the purpose of facilitating the description of the invention as a whole and not to define the limits thereof, reference being made to the appended claims for this purpose.

35 The drawing illustrates diagrammatically a circuit arrangement employed in carrying out the invention.

40 It is believed that the invention will be fully understood from the following detailed description of the operation.

When a subscriber at substation 1 initiates a call by removing his receiver from its switchhook, a circuit is closed for line relay 2 of the line switch extending from 45 grounded battery, left winding of said relay, back contact and inner upper armature of cut-off relay 3, substation apparatus 1, outer upper armature and back contact of relay 3, and right winding of relay 2, to 50 ground. By attracting its outer armature, relay 2 establishes a self-interrupting circuit for differential stepping magnet 4 extending from grounded battery, lower armature and back contact of cut-off relay 3,

front contact and outer armature of relay 55 2, right-winding, armature and back contact of magnet 4, to ground. Magnet 4 is energized and, preferably upon the back stroke, operates to step the brushes of the switch from the normal terminals on to the 60 first set of terminals to which a trunk is connected leading to a selector switch of any well-known construction. When brush 5 engages the contact bar 6 upon the first step of the switch, battery is applied to the conductor 7 through said brush which will provide a busy test for substation 1 should a final connector be set upon the multiple contacts individual to said substation. Engagement of brush 8 with contact bar 9 establishes another self-interrupting circuit for 65 stepping magnet 4 independent of the outer armature of line relay 2, so that should the subscriber at substation 1 replace his receiver upon the switchhook and thus deenergize the line relay, stepping magnet 4 will provide a busy test for substation 1 should a final connector be set upon the multiple contacts individual to said substation. Engagement of brush 8 with contact bar 9 establishes another self-interrupting circuit for stepping magnet 4 independent of the outer armature of line relay 2, so that should the subscriber at substation 1 replace his receiver upon the switchhook and thus deenergize the line relay, stepping magnet 4 will continue to operate the switch over the terminals of all trunks until the same is returned to its normal position.

If the first trunk leading to a succeeding 80 selector switch is busy, a relay of said selector switch, similar to relay 10, and the cut-off relay of the busy line switch will both be energized. Energization of the relay similar to relay 10 will remove battery 85 from its armature and back contact and thus prevent the closing of a circuit through the left differential winding of magnet 4. The ground at the cut-off relay of the busy line switch will be applied to the busy test terminal and thus shunt the cut-off relay 3. The stepping magnet 4 will therefore continue 90 to operate and step the brushes of the switch over the terminals of all busy trunks until an idle trunk is found. At this time the engagement of brush 11 with its associated terminal immediately closes the above-mentioned circuit through the left differential winding of magnet 4 which circuit is traceable from grounded battery, back contact 95 and armature of relay 10 at the selector switch, this relay being deenergized, brush 11, front contact and inner armature of relay 2 and left winding of magnet 4, to ground. This circuit through the differential winding of said magnet in conjunction with the circuit through the right winding thereof, will operate to prevent further energization of relay 10.

gization of the magnet and thus bring the switch to rest upon the terminals of the idle trunk. It will be noted that the closure of the last mentioned circuit will also momentarily establish a circuit to ground through the winding of the register magnet 12, but this magnet is adjusted so as not to operate on the battery potential of relay 10. Simultaneously with the closure of the circuit through the differential winding of stepping magnet 4, another circuit is also established for cut-off relay 3 extending from grounded battery, winding of relay 10, brush 13, and winding of relay 3, to ground. Relays 3 and 10 energize in this circuit and by attracting its armatures relay 3 extends the calling line through brushes 14 and 15 to the seized trunk. In so doing the circuit for relay 2 is opened and this relay then releases. In attracting its armature relay 10 removes battery from the back contact and thus prevents seizure of the selector switch by another line switch. After the calling line has been extended to the selector switch the subscriber at substation 1 may transmit sets of impulses to operate the succeeding switch or switches in any well-known manner until the call is established. At any time thereafter means are provided for operating the register magnet 12. This means is preferably shown as consisting of a normally open key 16 which may be placed at an operator's position and which, when depressed, will establish a circuit from a grounded battery of high potential, through key 16, front contact and armature of relay 10, brush 11 and winding of magnet 12, to ground.

The opening in any well-known manner of the circuit for relay 10 at the selector switch at the termination of the call, releases the relay together with cut-off relay 3. When relay 3 releases the self-interrupting circuit for magnet 4 extending from grounded battery at relay 3, through brush 8 and contact bar 9, will be established and the switch will be returned to normal as previously described.

On incoming calls to substation 1, if the line is idle, a circuit will be established for cut-off relay 3 extending from ground, through the winding of said relay, brush 13

and its normal contact, and conductor 7 to battery at the final connector switch which has been set upon the terminals of the line. Relay 3 will energize and, by attracting its lower armature, prevent operation of stepping magnet 4.

What is claimed is:

1. In a telephone exchange system, an automatic switch, a differentially wound stepping magnet for operating said switch, and means for energizing the windings of said magnet to prevent further operation thereof when the switch engages terminals of an idle line. 60

2. In a telephone exchange system, an automatic switch, a stepping magnet for the switch having a normally inactive differential winding, a circuit for operating said magnet, and means for energizing said differential winding to prevent operation of said magnet when the switch engages terminals of an idle line. 70

3. In a telephone exchange system, an automatic switch, a line relay therefor, a stepping magnet for said switch having a differential winding, a circuit for operating said stepping magnet extending through a contact of said line relay, and a second circuit extending through another contact of said line relay for energizing the differential winding of said stepping magnet to stop the operation thereof when the switch engages terminals of an idle line. 75

4. In a telephone exchange system, an automatic switch having a normal position, a line relay therefor, a stepping magnet for said switch having a differential winding, a circuit for operating said stepping magnet extending through a contact of said line relay, a second circuit extending through another contact of said line relay for energizing the differential winding of said stepping magnet to stop the operation thereof when the switch engages terminals of an idle line, and a third circuit independent of the contacts of said line relay for operating said stepping magnet to return the switch to normal. 90

In witness whereof, I hereunto subscribe my name this 4th day of August, A. D. 1919.

GEORGE THOMPSON.

DISCLAIMER.

1,383,677.—*George Thompson, Mount Vernon, N. Y. TELEPHONE-EXCHANGE SYSTEM.* Patent dated July 5, 1921. Disclaimer filed April 4, 1928, by the assignee, *Western Electric Company, Incorporated.*

Hereby enters this disclaimer to that part of the claims in said specification which are in the following words to wit:

"1. In a telephone exchange system, an automatic switch, a differentially wound stepping magnet for operating said switch, and means for energizing the windings of said magnet to prevent further operation thereof when the switch engages terminals of an idle line.

"2. In a telephone exchange system, an automatic switch, a stepping magnet for the switch having a normally inactive differential winding, a circuit for operating said magnet, and means for energizing said differential winding to prevent operation of said magnet when the switch engages terminals of an idle line."
